CHARLES L. JONES, OF PELHAM, NEW YORK, ASSIGNOR TO DRYICE EQUIPMENT CORPORATION, OF NEW YORK, N. Y., A CORPORATION OF DELAWARE

REFRIGERATING APPARATUS AND METHOD

Application filed March 25, 1930. Serial No. 438,704.

This invention relates to apparatus and methods for refrigeration by evaporation of solidified carbon dioxide and more specifically to refrigerators wherein ducts, hollow walls or interspaces are employed to circulate the resulting cold carbon dioxide gas, or mixtures thereof with air, in heat exchange relation with the space or products to be refrigerated.

10 A primary object of the invention is to produce a more uniform temperature throughout the refrigerated space or product, particularly as between the upper and lower regions thereof. As is well known, the upper 15 regions are likely to be too warm and the lower regions too cold, because, although the gas is usually evolved in an upper region of the refrigerator, it tends to flow downward in the ducts or interspaces before it has time 20 to effectually refrigerate said upper region.

Hence one feature of the invention involves retaining the freshly evolved gas in heat exchange relation to the upper portion of the refrigerated chamber to effectively refrigerate the same to the desired temperature before the gas is allowed to flow down in heat exchange relation to the lower portion.

Another object is to provide an apparatus in which bodies of the cold gas flowing from 30 the uppermost region will be retained in heat exchange relation with the sides of the refrigerated space or material at intermediate as well as at high and low levels, the design being such that the refrigerant values may be 35 distributed as required, by restraining means designed to form one or many pools of the down-flowing gas, thereby more or less interfering with the natural top-to-bottom circulation.

40 A still further object is to provide means whereby, particularly in an ice cream dispensing or freezing apparatus, the upper portion of the refrigerated chamber or product is effectually refrigerated first, by retaining 45 the down-flowing gas in a series of pools at desired levels, the upper leaking or cascading into the lower. In an ice cream dispenser, this permits the upper parts of the ice cream, which are most exposed in use, to 50 be maintained at the proper temperature,

while unnecessary over-freezing of the lower portion of the product may be avoided.

The above and other features of my invention may be more readily understood from the following description in connection with 55 the accompanying drawings, in which

Fig. 1 is a vertical section of a form of my invention as applied to an ordinary household refrigerator;

Figs. 2, 3, 4 and 5 are modifications showing the invention as applied to an ice cream dispensing cabinet, which may also be used as a freezer if desired.

In Fig. 1, a simple form of my invention is shown as embodied in a conventionally indicated refrigerator which may be somewhat like those shown in Martin Patents Nos. 1,752,015, 1,752,276 and 1,752,277, and somewhat resembling the construction shown in Fig. 7 of the latter; but with the important 70 difference that, as explained below, the thermo circulation is greatly modified. The outer casing 1 may be of any known or desired heat insulating construction, commonly employed for refrigerators. Within the 75 same is a container 2, preferably of sheet metal, of proper size to leave interspaces for circulation of gas in the spaces 4, 4a and 4b, which are preferably sealed off from the interior refrigerated storage space 5, and as in 80 said Martin patents, any side opening doors for access to this space will have the sheet metal container 2 carefully sealed, gas-tight, about the doorways. In an upper portion of this container in heat exchange relation with 85 the interior and in gas circulating relation to the interspace, is formed a container 3 for the solidified carbon dioxide.

The peculiarity of the arrangement is that this latter has an upwardly extending wall 90 6 which prevents the gas evolved in 3 from overflowing directly into the interspace 4b. Consequently, the freshly evolved gas must flow across the roof or ceiling 7 of the refrigerated space before it flows down through 4. 95 Further and more important, there is an upstanding ledge or retaining wall 8 in the nature of a baffle or dam, whereby a substantial layer of the freshly evolved gas is retained in contact with said ceiling 7 until the 100

added supplies of gas from 3 force overflow into downflow duct 4. Thence it flows across the bottom 4a and eventually up through 4b. At the top, part of the gas may recirculate 5 through the opening 9, the excess escaping either through leaks in the cover or through an overflow duct 10.

While the freshly evolved gas tends to flow in the path described, it will be noted 10 that the lefthand wall of the container 3 for the solidified carbon dioxide is in heat exchange relation with the duct 4b and that under certain conditions and with a certain proportion of parts it might be possible for the 15 heat absorbed through this wall to cool the rising gas sufficiently to cause a tendency to reverse circulation, in which case it might be possible to have a thin stream of cold gas flowing downward in contact with the wall of 20 container 2, while a reverse upward circulation 25 in the same duct might be following upward adjacent the outer wall. There may be a similar tendency to reverse flow from the duct 4 and across beneath the cover of the outer casing through the opening 9. Preferably, however, the proportioning of the 30 structure and the flow section of the passages 4, 4a and 4b will be such that the circulation will be as first above described, downward through 4, across through 4a and upward through 4b.

If the inner container 2 is spaced apart 35 from the outer casing 1 at front and rear, the front and rear interspaces may constitute the upflow portions of the circuit, partially or wholly or varying from time to time. In 40 fact, the remarkable uniformity of temperatures seems to be due in part at least to the mixing due to reversing tendencies of the thermo-circulation within each part of the interspace.

In most ordinary refrigerator structures 45 refrigerated by water ice or mechanical refrigeration, air is the only gas used in transferring heat, convection currents being usually obtained by thermo-circulation. In such systems the minimum temperature is 32° F. and the average say 40° F. In such case, the 50 coldest air is only about one-third of one per cent heavier than the warmest. Hence the thermo circulation is slow and the difference in temperature between the top and bottom of the refrigerator chamber is considerable, the bottom often being 10° F., or more, colder 55 than the top.

In systems employing solid carbon dioxide, either with or without a duct system, this condition is seriously aggravated because carbon dioxide gas is approximately 50% 60 heavier than air, at the same temperature, and independently of this, the temperature-density difference between the warmest and the coldest gas will be 20% to 25% as against .003 for air in the ordinary refrigerator.

65 It is obvious, therefore, that carbon dioxide

gas having once dropped to the bottom of the space or duct, does not rise again due to subsequent convection currents as readily as will air. Consequently, there is a tendency to a greater difference between the upper and lower regions of the refrigerator in a system using solid carbon dioxide were it not for the fact that sufficient gas can be sublimated to completely fill the interspaces or ducts surrounding the refrigerator chamber. However, to fill these ducts and maintain them filled requires that carbon dioxide gas be continuously sublimated and of course the more gas required the greater will be the 70 consumption of the refrigerant.

When the gas is first evolved, it naturally is coldest and its temperature rises as it circulates through the refrigerating system. By 75 my system, this first evolved or coldest gas is impeded in its flow or held against circulation, in the upper parts of the refrigerating structure, whereas, in the ordinary system the coldest gas or air, as the case may be, has a tendency to immediately drop to the 80 lowest point thereof, and must start from the bottom, to build up the refrigerating temperature.

85 It will be readily understood from the foregoing that by providing the baffles, suitably designed and located, the downward flow can be retarded or retained in pools so that the gas may be warmed to a desired extent before it reaches the bottom of the structure and may even be warmed enough to start localized reverse upward currents from intermediate levels. Hence the portions of the structure surrounded or bathed in the cold carbon dioxide gas at the top cannot be 90 warmed by heat from the outside, to a temperature higher than that of the coldest carbon dioxide gas in which the wall is bathed.

95 For the average use, it might be undesirable to establish the lowest refrigerating temperatures at the top and build downward, so, while this is possible, I prefer not to completely shut off the bottom portions of the refrigerator chamber, but only to retain desired amounts of the downflow gas, in local refrigerating zones, at different levels, the amounts and distribution being controlled 100 by the design of the gas-retarding means. In this way, I may obtain substantially uniform temperatures throughout the entire system or chamber; or any desired approximation of uniformity. In some of the tests run, I have even maintained a lower temperature 105 at the top than at the bottom, but the usual variance was less than 3° F. between the top and bottom of the refrigerator chamber, the bottom temperature being the lowest.

110 The modified arrangement shown in Fig. 2, like all the other modifications shown in the drawings, is applicable to almost any type of refrigerator, such as the household refrigerator of Fig. 1 or in fact any type in commer- 115

cial use. The modifications are here shown in connection with an ice cream cabinet for the purpose of illustration only. In Fig. 2, the refrigerator cabinet B is of any suitable 5 heat insulating material, formed with a carbon dioxide container 9 and ducts or carbon dioxide gas circulating spaces 10 formed by the walls 11 and 12 and, extending from the walls, are alternating baffles 13. It will be seen that as carbon dioxide gas is sublimated within the container 9 it will fill up the container and flow over the sides 12 into the spaces 10 completely filling said spaces and may be led back to the container 9 or vented 10 to the atmosphere through vents 14. The first gas to be sublimated will be trapped or retained in pools by the baffles 13 and the pocket formed by the baffles and the walls from which they extend will be filled with the cold carbon 15 dioxide gas before any of it is allowed to flow below them, thereby first refrigerating the upper section of the refrigerator chamber and subsequently retaining there the coldest carbon dioxide gas. In a system of this general 20 type, after the ducts have been filled with carbon dioxide gas, the tendency of the gas to sink to the bottom and the function performed by baffles of holding the coldest carbon dioxide gas in the upper portions will substantially 25 equalize the refrigerating effect in all parts of the refrigerator chamber, thereby producing an almost uniform temperature throughout the refrigerator chamber. In this 30 arrangement it is clear that natural top-to-bottom circulation is broken up, the coldest gas tending to cascade downward, while the warmer gas must find its way upward, countercurrent in intimate mixing as well as heat exchange relation with the downflow.

35 In Fig. 3 the baffles 15 are shown as extending almost completely across the spaces 16 formed by the walls 17 and 18. These baffles have, at any desired point therein, the holes or perforations 19 to allow constant flow of 40 gas downward while at the same time retaining substantially a solid wall of the gas around the upper portion of the refrigerator 45 chamber.

In Fig. 4 the baffles 20 are of different 50 lengths, the shortest one being at the top and the one next below being slightly longer to catch the overflow of gas from the one above. Each succeeding baffle is slightly longer than the one above, the bottom one being the long- 55 est.

Figs. 3 and 4 afford better opportunity for countercurrent up and down flow with less necessity for mixing than in Fig. 2.

In Fig. 5 I have shown a spiral baffle 21 60 which practically insures heat extraction by the length of the path that the cold carbon dioxide gas must traverse before reaching the bottom of the ducts. Instead of being an open baffle plate as shown, this could be a tube or, if desired, instead of being a spiral it

could be disposed in successive circles, each discharging downwardly into the next one below it. Fig. 5 shows still better opportunity for countercurrent thermo circulation with still less necessity for mixing of the up 70 and down currents.

The solid carbon dioxide compartment or the solid itself may be insulated to any desired extent, to lower the rate of gas evolution to protect the solid from the air. As shown in 75 Fig. 1, this insulation is indicated at *x* as a simple paper or cardboard wrapper for the solid. Obviously, any such heat insulating material, whether interior or exterior to the compartment 3, can be designed either to uniform thicknesses or varying thicknesses in different parts to cause greater or less heat absorption from any one of the walls of the compartment. For instance, the insulation between the solid and the lefthand wall of 80 compartment 3 in Fig. 1 could be made very thick, thereby proportionally decreasing the rate of heat absorption from the duct or interspace 4b.

I claim:

1. A double walled refrigerator chamber and a container for an intensely cold refrigerant, arranged for circulating cold atmosphere from the refrigerant container between said walls, and circulation impeding 95 baffles arranged substantially transversely to the direction of travel of the cold atmosphere and between said walls.

2. A refrigerator chamber and a container for an intensely cold refrigerant adjacent the upper portion thereof; with circulation spaces for the cold atmosphere from the refrigerant container, and circulation retarding baffles arranged substantially transversely to the direction of travel of the cold atmosphere 100 whereby the upper portions of the refrigerator chamber will be refrigerated first.

3. A refrigerator enclosing a solid carbon dioxide container, and downwardly extending circulation ducts into which carbon 110 dioxide gas from said container flows, and circulation impeding baffles within said ducts arranged transversely to the direction of flow of the carbon dioxide gas.

4. A refrigerating apparatus enclosing a 115 space to be refrigerated, and including a container of solid carbon dioxide arranged to absorb heat and discharge gas at a high level and ducts for circulation of the gas to cool said space, designed and arranged for retaining a body or bodies of the freshly evolved gas in heat absorbing relation with a high level portion of said space until said gas is warmed to a desired extent, but permitting overflow of excess gas to a lower level.

5. A refrigerating apparatus enclosing a 125 space to be refrigerated, and including a container of solid carbon dioxide arranged to absorb heat and discharge gas at a high level and ducts for circulation of the gas to cool 130

said space, designed and arranged for retaining a body or bodies of the freshly evolved gas in heat absorbing relation with a high level portion of said space until said gas is warmed to a desired extent, but permitting overflow of excess gas to a lower level, and a series of retaining baffles in the path of downflow of said gas arranged for overflow of gas from the higher baffles to the lower ones.

10. 6. A refrigerating apparatus enclosing a space to be refrigerated, and including a container of solid carbon dioxide arranged to absorb heat and discharge gas at a high level and ducts for circulation of the gas to cool said space, designed and arranged for retaining a body or bodies of the freshly evolved gas in heat absorbing relation with a high level portion of said space until said gas is warmed to a desired extent, but permitting overflow of excess gas to a lower level, and a series of retaining baffles in the path of downflow of said gas arranged for overflow of gas from the higher baffles to the lower ones, and arranged to retard both up and down thermo circulation in said duct.

7. A double-walled refrigerating apparatus enclosing a space to be refrigerated, a container of solid carbon dioxide arranged to absorb heat and discharge gas at a high level for circulation in the interspace between said walls, the flow paths being arranged for retaining a body or bodies of the freshly evolved gas in heat exchange relation with a high level portion of the refrigerated space but permitting overflow thereof to a lower level in said interspace.

8. A double-walled refrigerating apparatus enclosing a space to be refrigerated, a container of solid carbon dioxide arranged to absorb heat and discharge gas at a high level for circulation in the interspace between said walls, and a series of retaining baffles in the path of downflow of said gas arranged for overflow of gas from the higher baffles to the lower ones.

9. A double-walled refrigerating apparatus enclosing a space to be refrigerated, a container of solid carbon dioxide arranged to absorb heat and discharge gas at a high level for circulation in the interspace between said walls, and a series of retaining baffles in the path of downflow of said gas arranged for overflow of gas from the higher baffles to the lower ones, and baffles arranged to retard both up and down thermo circulation in said interspace.

10. A double-walled refrigerating apparatus enclosing a space to be refrigerated, a container of solid carbon dioxide arranged to absorb heat and discharge gas at a high level for circulation in the interspace between said walls, and baffles arranged to hold and permit overflow of gas, down flowing adjacent the inner wall of the interspace and to bring the overflow into heat exchange and mixing rela-

tion to warmer gas tending to flow upward adjacent the outer wall of said interspace.

11. Refrigerating apparatus, including outer and inner containers formed and arranged to confine and permit circulation of gas between said containers, in combination with a container enclosing solid carbon dioxide arranged so that said solid may absorb heat derived from the inner container and arranged for downflow of the resulting dry cold gas between the containers; and retaining means in the path of downflow of said gas to establish high level refrigerant zones about said inner container.

12. Refrigerating apparatus, including outer and inner containers formed and arranged to confine and permit circulation of gas between said containers, in combination with a container enclosing solid carbon dioxide arranged so that said solid may absorb heat derived from the inner container and arranged for downflow of the resulting dry cold gas between the containers, and substantially transversely extending baffles in the path of downflow of said gas.

13. A refrigerator enclosing a chamber to be refrigerated and a solid carbon dioxide container at a high level therein, and provided with a carbon dioxide gas circulation duct leading from the carbon dioxide chamber and substantially surrounding the refrigerator chamber, a baffle near the inlet end of said duct whereby carbon dioxide gas is retained in the upper portion of said duct and a vent in said duct at a high level point of the gas circulation.

14. A double-walled refrigerator enclosing a chamber to be refrigerated and a solid carbon dioxide container absorbing heat and discharging gas at a high level therein, and formed or provided with gas circulation space between the walls and with circulation impeding baffles alternately arranged on opposite walls of said circulation space.

15. A double-walled refrigerator enclosing a chamber to be refrigerated and a solid carbon dioxide container absorbing heat and discharging gas at a high level therein, and formed or provided with gas circulation space between the walls and with circulation impeding baffles closing most of said space and perforations in said baffles.

16. A double-walled refrigerator enclosing a chamber to be refrigerated and a solid carbon dioxide container absorbing heat and discharging gas at a high level therein, and formed or provided with gas circulation space between the walls and with circulation impeding baffles extending outwardly progressively from the upper part of said circulation space, downward, whereby carbon dioxide gas overflowing from one of said baffles will be caught by the next baffle below.

17. A double-walled refrigerator enclosing a chamber to be refrigerated and a solid car-

- bon dioxide container absorbing heat and discharging gas at a high level therein, and formed or provided with gas circulation space between the walls and with circulation impeding baffles spirally arranged about the inner walls of said space. 5
18. A method of insulating and cooling a refrigerated space, which includes enclosing solid carbon dioxide to absorb heat and discharge refrigerant gas at a high level with respect to said space, and guiding and restraining said gas to maintain a pool or body of the outflowing cold gas in heat exchange relation with a high level portion of said refrigerated space. 10
19. A method of insulating and cooling a refrigerated space, which includes enclosing solid carbon dioxide to absorb heat and discharge refrigerant gas at a high level with respect to said space and guiding and restraining downflow of said gas to maintain a pool or body of the freshly evolved gas in heat exchange relation with a higher level portion than said refrigerated space, and guiding the overflow of gas from said pool to maintain a continuous renewed insulating layer of the gas interposed between the refrigerated space and the exterior. 15
20. A method of insulating and cooling a refrigerated space, which includes enclosing solid carbon dioxide to absorb heat and discharge refrigerant gas at a high level with respect to said space, guiding and baffling downflow of freshly evolved gas about and in heat exchange relation with the refrigerated space, thereby greatly increasing the amount of heat absorbed by the gas in the upper portion of the refrigerated space. 20
21. A method of insulating and cooling a refrigerated space, which includes enclosing solid carbon dioxide to absorb heat and discharge refrigerant gas at a high level with respect to said space, and guiding and restraining downflow of said gas to maintain a pool or body of the freshly evolved gas in heat exchange relation with a higher level portion than said refrigerated space, and guiding the overflow of gas from said pool to maintain a continuous renewed insulating layer of the gas interposed between the refrigerated space and the exterior. 25
22. A method of insulating and cooling a refrigerated space, which includes enclosing solid carbon dioxide in heat exchange relation with said space and guiding and restraining gas evaporated from the solid to maintain a plurality of refrigerant zones of freshly evolved gas encircling said space at different levels. 30
23. A method of insulating and cooling a refrigerated space, which includes enclosing solid carbon dioxide in heat exchange relation with said space, and guiding and restraining gas evaporated from the solid to maintain a plurality of refrigerant zones of 35
- freshly evolved gas encircling said space at different levels, and utilizing the excess gas to maintain a continuously renewed insulating layer of the gas interposed between the refrigerated space and the exterior. 70
24. A method of insulating and cooling a refrigerated space, which includes enclosing solid carbon dioxide in heat exchange relation with said space, and guiding and restraining gas evaporated from the solid to maintain a plurality of refrigerant zones of freshly evolved gas encircling said space at different levels, confining the excess gas to maintain a continuously renewed insulating layer of the gas interposed between the refrigerated space and the exterior, and permitting final escape of said excess by high level overflow. 75
25. The method of refrigerating by solid carbon dioxide, which includes circulating the freshly sublimated carbon dioxide gas through ducts substantially surrounding the refrigerator chamber, retaining part of the freshly sublimated carbon dioxide gas at a high level in said ducts while permitting overflow of part of it to a lower level and impeding the subsequent circulation of said gas. 80
26. A refrigerating apparatus for insulating and cooling a space comprising a chamber for solid carbon dioxide, said chamber being so arranged as to effect the absorption of heat from and a discharge of refrigerant gas at a high level with respect to said space, and means for guiding and restraining said gas to effect the maintenance of a pool or body of overflowing cold gas in a heat exchange relation with a high level portion of said space. 85
